[57] CLAIM

The ornamental design for a spool for a spinning fishing reel, as shown and described.

DESCRIPTION

FIG. 1 is a perspective view of the rear and a portion of the circumferential surface of a spool for a spinning fishing reel showing my new design, it being understood that the surface is uniform throughout the circumference of the spool;

FIG. 2 is a perspective view of the front and a portion of the circumferential surface thereof;

FIG. 3 is a side elevational view thereof;

FIG. 4 is a rear elevational view thereof;

FIG. 5 is a front elevational view thereof; and,

FIG. 6 is a sectional view taken along the line 6—6 in FIG. 4 thereof.
